UNITED STATES PATENT OFFICE.

DOCTOR M. WILCOX, OF MENOMINEE, MICHIGAN.

DESIGN FOR A TOOTH-BRUSH HOLDER.

51,990.

Specification for Design.

Patented Apr. 23, 1918.

Application filed October 9, 1917. Serial No. 195,645. Term of patent 14 years.

To all whom it may concern:

Be it known that I, DOCTOR M. WILCOX, a citizen of the United States, and a resident of Menominee, county of Menominee, and State of Michigan, have invented a new, original, and ornamental Design for a Tooth-Brush Holder, of which the following is a specification, reference being had to the accompanying drawings, forming a part thereof.

The uppermost figure on the sheet of drawings is a perspective view of a tooth brush holder showing my new design; and the lowermost picture on the sheet of drawings is a plan view of the tooth brush holder showing my new design.

I claim:

The ornamental design for a tooth brush holder substantially as shown.

D. M. WILCOX.
